TAR EXTRACTOR

William R. Pendry, Shaker Heights, Ohio

Application November 27, 1933, Serial No. 700,000

4 Claims. (Cl. 183—96)

This invention relates to tar extractors of the type having a casing in which there is an up-standing pipe over which a bell is positioned, the gases from which the tar is to be extracted entering the casing through this pipe, and this bell, which is of a perforate construction, functioning to extract the tar. The casing has a suitable outlet and is filled with a liquid forming a seal between the pipe and the bell. This type is called 5 a "Pelouze and Audouin" tar extractor.

The above mentioned bell is ordinarily a suitably shaped frame having flat, open sides which mount tar-extracting plate-packs. Since it is desirable to use two or more of these plate-packs 15 in series, this frame is usually constructed from riveted parts forming double end-structures, one within the other. Each of these structures mounts one of the plate-packs, the latter each comprising two plates having respectively offset perforations and separated by a number of flat bars, these parts all being riveted together to form 20 a whole.

It follows that the repair or cleaning of this bell is a tedious operation requiring skilled labor, 25 and cannot be advantageously performed in the ordinary machine shop of a by-product coke works, it being understood that extractors of the type under discussion are customarily used as the final step in the removal of tar from coke-oven 30 gases.

One of the objects of the present inventor is to improve the construction of such a tar-extractor bell, simplicity and easy cleaning and repair being the primary aims. Other objects may be inferred.

An example of a tar-extractor bell constructed according to the present invention is illustrated by the accompanying drawings, the various figures being as follows:

40 Figure 1 is a sectional view of a tar-extractor. Figure 2 is a cross-section from the line II—II in Figure 1.

Figure 3 is a broken sectional view of one of the bells.

45 Figure 4 is a top view of Figure 3.

Figure 5 is an enlarged cross-section taken on the line V—V in Figure 3.

Figures 6 through 9 are details of one of the plate-packs.

50 A Pelouze and Audouin tar-extractor is illustrated by the first figures. It includes a casing 1 having an outlet 2 and provided with a plurality of upstanding pipes 3. The gases from which the tar is to be extracted are fed to these pipes 55 by a manifold 4 supplied by an inlet 5. A bell 6

is positioned over each of these pipes 3 by a spider 7 which is manipulated through a connecting-rod 8, walking beam 9 and controlling rod 10, the latter being operated by a hand-wheel 11 with which it is in screw-threaded engagement. A 5 liquid 12, such as tar, is maintained in the casing 1 for the purpose of forming a seal between the bottom portions of the bells 6 and the sides of the pipes 3. The level of this liquid may be adjusted by decanter cocks 13.

The operation of the above described tar-extractor is pretty well known. The gases flow up through the pipes 3, filter through the bells 6 and leave the casing 1 by the outlet 2. The bells are raised and lowered, and the liquid level of 15 the seal is adjusted, according to the volume or tar content of the gases being cleaned. The bells 6 operate on the principle that impingement against a flat surface of gases carrying dispersed, suspended tar, will cause condensation and collection of this tar. Discovery of this principle 20 is generally attributed to Pelouze and Audouin, this type of extractor being therefore distinguished by their names.

As previously mentioned, the present invention 25 is concerned with improving the bells 6, the foregoing being to disclose their use to an uninformed reader. Sometimes a single large bell is used, but oftener a number are used in the manner described.

30 Each of the bells 6 includes a frame 14 providing open ends and sides respectively bounded by flanges 15 and 16 having spaced holes 15^a and 16^a. A closing plate 17 is constructed for application to either of the ends of the frame 14 and has holes 17^a arranged to register with the holes 15^a in the flanges 15 bounding these ends. This closing plate also has central holes 17^b for connection with the positioning device of a tar-extractor by bolts, for instance, with the spider 7 of 40 the one illustrated. This closing plate may be fastened by bolts 15^b to either end of the frame 14, so as to close the same.

45 A plurality of tar-extracting plate-packs 18 are constructed for application to the sides of the frame 14, and have holes 18^a arranged for registration with the holes 16^a in the flanges 16 by bolts 19 which pass through the holes 18^a and 16^a. Since it is usually desirable to use at least two of the plate-packs in series, two or more of 50 the same may be fastened to the flanges 16 by the bolts 19, separators 20, identical with separators 22 except ordinarily several times thicker, being used between the respective packs to secure their proper separation.

The advantages of the bell as so far described include the ability to reverse it should its portion being used become leaky. That is to say, the plate 17 may be unbolted from the used end of the bell, the latter reversed and the plate rebolted to its other end. This end will be practically new, since it has been immersed in the liquid seal during its prior use. Another advantage is the ability to use any number of the plate-packs in series. This may be done simply by the use of sufficiently long bolts and a sufficient number of spacers.

The plate-packs 18 are different from those usually used. They each consist of three similarly sized plates 21, 22 and 23, having mutually registering holes forming the holes 18^a previously mentioned. The other two of these plates, 21 and 23, have the usual mutually offset perforations. The inner one of these plates, 22, has openings 20 permitting the flow of fluid through all of the plates by way of the offset perforations mentioned. This plate 22 is integral throughout and functions as a separator for the other two, it being understood that the plate 22 is in the form of an open frame so as to permit free fluid passage.

Since it is not desirable to depend on the bolts 19 to interfasten the respective plates, the latter may all have mutually registering, centrally positioned bolt holes 24, and bolts 25 (Figures 3 and 5) may be passed through these holes to clamp the plates together. When the plates are used in multiple as illustrated, these bolts may pass through two of the packs and the separators 20 used to separate the respective packs. Thus, a unitary installation results which may be dismounted from the frame as a whole by the removal of the bolts 19.

A heavy binder plate 27, which is shaped similarly to the plate-packs and has similarly positioned holes 18^b, may be applied over the bolts 19 for the purpose of strengthening the bell as a whole.

Among the advantages of the new plate-packs are the ease of installing and removing them when installed in series, and the ability to separate the individual plates for cleaning purposes, without necessitating the use of skilled labor.

I claim:

50 1. A tar-extractor bell providing open ends,

and including in combination a closing plate constructed to fit either of said ends and adapted for connection with the positioning device of a tar-extractor, and releasable means for fastening said plate to either of said ends.

2. A tar extractor bell including the combination of a frame providing open ends and sides, a closing member constructed for application to either of the ends of said frame, tar-extracting plate-packs constructed for application to the sides of said frame, means for fastening said member to either of the ends of said frame, means for fastening said packs to the sides of said frame, and separators constructed for application between a plurality of said packs when the same are applied in multiple to any one of the sides of said frame.

3. A tar extractor bell including the combination of a frame providing open ends and sides, a closing member constructed for application to either of the ends of said frame, tar-extracting plate-packs constructed for application to the sides of said frame, releasable means for fastening said member to either of the ends of said frame, and means for fastening said packs to the sides of said frame.

4. A tar-extractor bell including the combination of a frame providing open ends and sides respectively bounded by flanges having spaced holes, a closing plate constructed for application to either of said ends and having holes arranged to register with the holes in the flanges bounding these ends, said closing plate being adapted for connection with the positioning device of a tar-extractor, a plurality of tar-extracting plate-packs constructed for application to said sides and having holes arranged for registration with the holes in the flanges bounding these sides, bolts for fastening said closing plate to the flanges bounding said ends and said plate-packs to the flanges bounding said sides when inserted through the respectively registered holes in each, and separators apertured to receive the bolts when inserted through the holes in said plate-packs and the flanges bounding said open sides, said separators being for the purpose of separating said plate-packs when applied in multiple to any one of said sides.

WILLIAM R. PENDRY.
